(57) **CLAIM**

The ornamental design for a packaging container as shown and described.

DESCRIPTION

FIG. 1 is a perspective view of a packaging container, showing our new design.

FIG. 2 is a perspective view of FIG. 1 thereof showing the cap off.

FIG. 3 is a front view of FIG. 1 thereof.

FIG. 4 is a top plan view of FIG. 1 thereof.

FIG. 5 is a bottom plan view of FIG. 1 thereof.

FIG. 6 is a right side view of FIG. 1 thereof.

FIG. 7 is a cross-sectional view taken along line 7-7 of FIG. 4 thereof.

FIG. 8 is an enlarged cross-sectional view taken along line 8-8 of FIG. 3 thereof.

FIG. 9 is an enlarged cross-sectional view taken along line 9-9 of FIG. 3 thereof.

FIG. 10 is a cross-sectional view taken along line 10-10 of FIG. 4 thereof.

FIG. 11 is a cross-sectional view taken along line 11-11 of FIG. 4 thereof.

FIG. 12 is an enlarged view of portion 12-12 in FIG. 10 thereof.

FIG. 13 is an enlarged view of portion 13-13 in FIG. 11 thereof.

FIG. 14 is a perspective view of a second embodiment of the packaging container.

FIG. 15 is a front view of FIG. 14 thereof.

FIG. 16 is a rear view of FIG. 14 thereof.

FIG. 17 is a top plan view of FIG. 14 thereof.

FIG. 18 is a bottom plan view of FIG. 14 thereof.

FIG. 19 is a right side view of FIG. 14 thereof; and,

(Continued)

FIG. 20 is a left side view of FIG. 14 thereof.
 A rear view of the first embodiment of FIG. 1 is omitted because it appears the same as the front view in FIG. 3.
 A left side view of the first embodiment of FIG. 1 is omitted because it appears the same as the right side view in FIG. 6.
 The broken lines in FIGS. 10 and 11 represent the boundary of the enlargement and form no part of the claimed design.

1 Claim, 20 Drawing Sheets
